UNITED STATES PATENT OFFICE.

RAYMOND N. EHRHART, OF EDGEWOOD, PENNSYLVANIA, ASSIGNOR TO ELLIOTT COMPANY, OF PITTSBURGH, PENNSYLVANIA, A CORPORATION OF PENNSYLVANIA.

FLUID-COMPRESSING APPARATUS.

Application filed December 7, 1921, Serial No. 520,530. Renewed December 19, 1924.

To all whom it may concern:

Be it known that I, RAYMOND N. EHRHART, a citizen of the United States, residing at Edgewood, Allegheny County, Pennsylvania, have invented a new and useful Improvement in Fluid-Compressing Apparatus, of which the following is a full, clear, and exact description.

The present invention relates broadly to fluid compressing apparatus, and more particularly to ejectors adapted for use with condenser and similar installations where it is desired to maintain certain pressure conditions below atmospheric or effect the removal of air or other fluids.

It has heretofore been proposed to construct single stage ejectors having long and short nozzle structures so arranged that the short nozzles effect preliminary compression of fluids entrained by their operation and deliver the entrained and entraining fluids directly to long nozzle structures without any loss of efficiency such as produced by first converting the velocity energy established by the short nozzle structure into pressure energy, and then reconverting into velocity energy by the long nozzle structure. Such constructions, although possessing many advantageous features, have not been proportioned whereby a highly efficient compressing action has been secured throughout a long range and at higher pressures.

The present invention, while embodying certain of the features of such prior constructions, relates primarily to the relative proportioning of the respective parts whereby high efficiency is obtained when compressing great amounts of air from low pressures, and higher efficiency, than has heretofore been obtained, is obtained when compressing great amounts of air from higher pressures, such, for example, as from 2 to 5 inches of mercury.

The foregoing and other objects of the present invention, together with their attendant advantages, will be apparent as the invention becomes better understood by reference to the accompanying specification

and drawings forming a part thereof, it being premised that changes may be made in the details of construction and manner of operation without departing from the spirit of my invention or the scope of my broader claims.

Figure 1 is a longitudinal sectional view, partly broken away, through an ejector constructed in accordance with the present invention;

Figure 2 is a transverse sectional view on the line II—II of Figure 1, looking in the direction of the arrows;

Figure 3 is a transverse sectional view on the line III—III of Figure 1, looking in the direction of the arrows, and

Figure 4 is a graphic illustration of the operation of an ejector embodying the present invention.

Referring more particularly to Figures 1 to 3 of the drawings, there is illustrated an ejector comprising a diffuser structure having a converging portion 2 and a diverging portion 3 connected by a throat portion 4. The open end of the converging portion 2 of the diffuser communicates with a connection 5 through which the fluid to be compressed or entrained enters the ejector.

Carried by the ejector structure is a steam chamber 6 having a suitable opening for the admission of the steam to be used as the compressing or entraining medium. Connected with the steam chamber 6 is a plurality of short accelerating nozzles 7 which may project slightly into the converging portion of the diffuser, if desired, but which preferably terminate outside of the diffuser, as shown. Also connected with the steam chamber is a plurality of long propelling nozzles 8 which project well into the converging portion of the diffuser. Both the long and short nozzles are divergent, making them suitable for expanding steam at a relatively great pressure to the low pressure existing in the suction chamber of the ejector.

As before pointed out, the section of the diffuser having the smallest diameter is termed the throat. The cross-sectional area

at this point is termed the throat area. The portion of the convergent end of the diffuser at the end of the long nozzles 8, and lying slightly beyond the section line 5 III—III of Figure 1, is the mouth of the diffuser. The mouth area designates the area of the diffuser at this point after the cross-sectional area of the long nozzles is deducted therefrom. This mouth area is 10 the passage through which the steam is delivered from the short nozzles 7 to the long nozzles 8, and is substantially as indicated by the shaded portion in Figure 3.

The present ejector is so proportioned 15 that the throat area of the diffuser is greater than the outlet area of the long nozzles, but is less than the mouth area. This necessarily means that the mouth area must be greater than the outlet area of the long 20 nozzles.

Calculations which have been computed for the construction of expanding nozzles call for a ratio of divergence which is greater than that which I have found to 25 produce the best results. For example, the short nozzles which expand steam from the steam line pressure, which may be 140 pounds per square inch absolute, to a pressure of 1 inch of mercury, should theoretically have a ratio of divergence of substantially 32. In other words, the outlet area 30 of these nozzles should be substantially 32 times their throat area. My experiments have shown, however, that better results are obtained when the outlet area is approximately 10 times that of the throat area, but 35 that good results are obtained when the ratio of divergence varies from 8 to 32. In any case, however, for efficient results, I find that the ratio of divergence should be materially less than that theoretically required 40 when expanding from the initial steam pressure to the pressure at the termination of the nozzles. However, irrespective of the 45 departure of the present nozzles from the theoretical calculation, I find that both sets of nozzles should have a ratio of divergence which is within 30% of each other.

When nozzles are operated with a divergence ratio less than that called for by calculation incident to initial steam pressure and discharge pressure, such nozzles are spoken of as being under-expanded. I find that for the best results, the long nozzles 50 should be less under-expanded than the short nozzles, preferably, however, within 30% of each other as set forth.

With steam pressures for the propelling 60 nozzles varying from 100 to 140 pounds per square inch absolute, the long nozzles should pass more steam than the short nozzles, preferably more than two times as much, but considerably less than three times as much. The higher the steam pressure, the greater is the amount of steam required 65

through the shorter nozzles in relation to the longer nozzles. For a pressure of approximately 140 pounds per square inch absolute of the propelling steam, the long nozzles should pass about 2.66 times as much 70 steam as the short nozzles. For a 200 pound pressure the long nozzles should pass approximately twice as much steam as the short nozzles.

For efficient results, it will be understood 75 that the total mouth area with a construction such as herein disclosed, may be divided into five theoretical divisions, which I may term interstice areas, which interstice areas take care of the flow of entrained and entraining fluid from the short or accelerating nozzles. These interstice areas are 80 designed and proportioned with respect to the volume of flow through the corresponding accelerating nozzles which deliver 85 thereto, so as to adequately take care of said flow, and are also proportioned with respect one to the other in such manner that no interstice area is less than fifty per cent (50%) nor more than one hundred and 90 fifty per cent (150%) of the average interstice area, when all of the accelerating nozzles deliver the same amount of steam. This ensures the steam from all of the accelerating nozzles reaching the compressing 95 nozzles at substantially the same velocity. This velocity for efficient operation should be greater than 750 feet per second and less than 2000 feet per second, approximately 1500 feet per second being very effective. 100

In an ejector of this type, I find that the shorter nozzles effect a material compression of the entrained fluid, so that when exhausting from a range of from 1 to 5 inches of mercury they effect a compression of the 105 fluid before it is delivered for entrainment to the larger nozzles of from 3 to 10 inches of mercury. In general, the ratio of compression accomplished by the first nozzles is less than 4, said ratio becoming less as the 110 amount of fluid entrained or compressed, increases. For good performance it is necessary to have a ratio of compression of at least 2 for the short set of nozzles. For 115 example, if the ratio of compression for the short set of nozzles is three when exhausting from a pressure of 1 inch of mercury, fluid would be delivered to the long nozzles at a pressure of 3 inches of mercury. With a construction such as above set forth, there 120 is provided an ejector producing results substantially as illustrated graphically in Figure 4 by the curve A—A. In this figure, the vertical scale shows the absolute pressure, in inches of mercury, obtained in 125 the suction chamber of the ejector when compressing the entrained fluid, such as air, to a pressure slightly above that of the atmosphere. The horizontal scale shows the amount of air compressed by approximately 130

650 pounds of moving steam at approximately 140 pounds absolute pressure. In this figure there is also shown a comparison curve B-B which illustrates the results obtained as the throat area of the long nozzles increases with respect to that of the short nozzles, and as the outlet area of the long nozzles more nearly approaches or becomes greater than the throat area, and the mouth area decreases with respect to the long nozzle outlet area or with respect to the diffuser throat area. With such changes it will be apparent that the efficiency of the ejector is very slightly increased at low pressures, but materially decreased at higher pressures such as from 2 to 5 inches of mercury. With this comparison curve, it becomes apparent that the proportioning herein set forth is of considerable importance as it provides an ejector having a materially greater operating range with much greater efficiency than existing ejectors, at higher pressures, and substantially the same efficiency, as existing ejectors, at lower pressures.

It is understood that by long and short nozzles as used throughout the specification and claims, I mean, respectively, those nozzles terminating nearer and farther from the throat of the diffuser.

I claim:

1. In a single stage ejector, diffuser structure, long nozzle structure projecting well into said diffuser structure, and short nozzle structure, the area of the diffuser structure at its throat being greater than the outlet area of the long nozzle structure, substantially as described.

2. In a single stage ejector, diffuser structure, long nozzle structure projecting well into said diffuser structure, and short nozzle structure, the outlet area of the long nozzle structure being less than the area of said diffuser at its throat and less than the mouth area of the diffuser, substantially as described.

3. In a single stage ejector, diffuser structure, long and short diverging nozzle structure, said long nozzle structure projecting well into the diffuser, the outlet area of the long nozzle structure being greater than the outlet area of the short nozzle structure and less than the area of said diffuser at its throat, substantially as described.

4. In a single stage ejector, diffuser structure, long nozzle structure projecting well into said diffuser structure and forming a mouth, and short nozzle structure, the area of the diffuser at its throat being less than the area of said mouth, substantially as described.

5. In a single stage ejector, a diffuser, long and short nozzle structure, said long nozzle structure projecting well into said diffuser and forming a mouth, the mouth

area being greater than the outlet area of the long nozzle structure, substantially as described.

6. In a single stage ejector, a diffuser structure, diverging long and short nozzle structure, said long nozzle structure projecting well into said diffuser structure, the ratio of divergence of said nozzle structures being within 30% of one another, substantially as described.

7. In a single stage ejector, a diffuser structure, long and short diverging nozzle structure, the long nozzle structure projecting well into said diffuser structure, and both of said nozzle structures being proportioned so that the ratio of divergence is within a range of from 8 to 32, substantially as described.

8. In a single stage ejector, a diffuser structure, long and short diverging nozzle structure, the long nozzle structure projecting well into said diffuser structure, and both of said nozzle structures being proportioned so that the ratio of divergence is less than 32, substantially as described.

9. In a single stage ejector, a diffuser structure, under expanded long and short diverging nozzle structure, the long nozzle structure projecting well into said diffuser structure, and both of said nozzle structures being proportioned so that the ratio of divergence is greater than 8, substantially as described.

10. In a single stage ejector, a diffuser structure, long and short nozzle structure, all of said nozzle structures being under-expanded, substantially as described.

11. In a single stage ejector, diffuser structure, long nozzle structure, and short nozzle structure, said long nozzle structure projecting well into the diffuser, both of said nozzle structures being under-expanded with the short nozzle structure under-expanded to a greater extent than the long nozzle structure, substantially as described.

12. In a single stage ejector, diffuser structure, long nozzle structure, and short nozzle structure, said long nozzle structure projecting well into the diffuser, both of said nozzle structure being under-expanded with the short nozzle structure under-expanded to a greater extent than the long nozzle structure, the ratios of divergence of said nozzle structures being within 30% of one another, substantially as described.

13. In a single stage ejector, diffuser structure, long and short nozzle structure, said long nozzle structure projecting well into said diffuser structure and passing more than 2 but less than 3 times as much propelling fluid as said short nozzle structure, substantially as described.

14. In a single stage ejector, a diffuser structure, long nozzle structure projecting well into said diffuser, short nozzle struc-

ture cooperating therewith for delivering fluid to the long nozzle structure at a velocity of from 750 to 2000 feet per second, both of said nozzle structures being under-
5 expanded and having divergence ratios within 30% of one another, the long nozzle structure forming a mouth having an area

greater than the outlet area of the long nozzle structure and greater than the throat area of said diffuser, substantially as de-
10 scribed.

In testimony whereof I have hereunto set my hand.

RAYMOND N. EHRHART.
